UNITED STATES PATENT OFFICE

UDO K. JOHANNSEN, OF CORTLAND, NEW YORK, ASSIGNOR TO THE BREWER-TITCHENER CORPORATION, OF CORTLAND, NEW YORK, A CORPORATION OF NEW YORK

TRIM FRAME FOR PANELS

Application filed January 8, 1932. Serial No. 585,585.

This invention relates to the art of a built-up moulding for panels and is more particularly directed to improvements in a decorative, segmental framework intended to enhance the trim of automobile license plates and which self-contained frame comprises but four intersecting sections that can be economically fabricated and rapidly secured together at their intersecting regions without surface defacement by welds, rivets or need of separately formed corner pieces or the like superfluous keeper means.

The primary object of my invention is to provide for a smartly designed trim frame or automobile accessory of the character indicated and one that can be cooperatively applied to the perimeter of a beaded panel. My frame design is such that it can be made up to any desired dimension by the use of relatively few forming dies and still provide for rounded corner regions. The present segmental structure is preferably struck up from strip-stock into complementary pairs of dished side and cross bar sections of similar profile having their respective ends overlappingly nested and neatly united by flexible prong-like tongue or equivalent fastening means, the terminals of said bars being offset and so disposed that their respective front faces fall into substantial alignment. Said moulding-like frame is preferably supported upon its embraced panel and secured thereto by the use of a plurality of spaced prongs depending from the perimeter of the frame assembly, that may be overlappingly inturned against the rear of the mounted panel.

Said improvements further consist in alternative frame securing features, all of which will hereinafter be disclosed in detail. Reference is had to the accompanying two sheets of drawings, which are illustrative of specific embodiments of my invention, and in which drawings:

Fig. 1 shows an elevational front view of my preferred style of frame assembly as applied around a conventional license plate, while Fig. 2 represents a rear view thereof with the frame prongs crimped inwardly to mount the plate.

Fig. 3 is a fragmental sectional view of said assembly as taken along line 3—3 of Fig. 1.

Fig. 4 illustrates an enlarged corner detail of Fig. 2 and the relation of the frame prongs prior to their being crimped inwardly. 55

Figs. 5 and 6 respectively represent a sidebar and a cross-bar blank as stamped up from flat strip-stock.

Figs. 7 and 8 are typical perspective views of the respective blank ends after they have 60 been formed up and made ready for assembly into the rectangular Fig. 1 framework.

Fig. 9 shows the manner in which my framework may be sprung to make the license plate rattleproof. 65

Fig. 10 represents a modified corner detail in which my segmental bars are united by special bolts instead of tongues, and Figs. 11 and 12 show how these differently shaped bar ends may be brought into cooperative relationship. 70

Figs. 13 to 15 disclose still another style of my frame corner region in which the offset socket element of the intersecting bars is 75 reversely formed.

Referring first to Figs. 1 to 8 inclusive, they collectively show a built-up framework or endless moulding of channel-like profile adapted to trim the marginal edge of the elongated license plate 10 or any other similar panel. The prevailing state identification plates are commonly provided with an endless marginal bead 11 and with an adjacent inner groove such as 12. The corner region of the plate perimeter is generally rounded off as represented at 13 by dotted outline in Fig. 4. The panel 10 is placed behind the fenestration of my open rectangular skeleton frame of which the upstanding pairs of relatively long corner prongs 14 and 15 are crimped over the panel edge in the fashion indicated in Fig. 2. My segmental framework is characterized by the use of side-bars and cross-bars such as 16 and 17 respectively and which bars are kept rectilinear except at the overlapping terminal regions thereof. 80

Short supplemental bar-tenons or tongues such as 18 and 19 respectively, may be used to permanently clinch together the overlapping nested frame-bar ends. This built-up 85

method materially reduces production costs over an integrally stamped frame, which latter involves considerable waste in center plate stock.

5 The structural aspects of my sectional frame-bars and mode of making same, may be explained in connection with Figs. 5 and 6. The first named figure shows a strip-like blank 20 that is stamped out of flat cold-rolled strip-stock of suitable sheet-metal gauge and width "w". This blank is preferably given a dished or channel-like profile comprising a relatively flat web element 16A disposed between upstanding marginal flanges such as 16B and the respective ends of which web are raised at 18 as shown in Fig. 7 to constitute the rectilinear side-bar 16. The opposite blank ends may be similarly but reversely sheared while still flat to include a relatively short end-tongue 18, a side-tenon or tongue 19, and an intermediate relatively long extension or prong 14 that is parted by an edge indentation 21, all of which elements are kept within the confines of the strip width "w". 20 The dotted outline indicates the corresponding die contour and the manner of successively parting said strip in a plurality of such blanks of any desired overall length, depending upon the successive feed-spacing that is given to the strip-stock.

Fig. 6 represents the corresponding flat shape imparted to my relatively shorter blank 22, which may be kept free of any tongues but may be made to terminate in the oppositely disposed prongs 15 and is also provided with spaced tongue receiving apertures such as 23. Between such apertures and their respective overhanging prongs, the blank perimeter is given a rounded nose-like contour such as 24 which shape in turn allows of giving my frame corner a rounded perimetric formation having a radius substantially equal to the strip width "w". The blank 22 is then struck up by the use of suitable dies into a dished cross-bar 17 of channel shaped profile having a relatively flat web element 17A and reversely disposed terminals with the prongs 15 thrown downwardly as shown in Fig. 8 where the end region of the innermost web flange 17B is cut away to clear its mated bar. Each terminal of the side-bar 16 may be transversely offset at 29 to form a bar extension 26 and constitute an interiorly socketed means adapted to overlie and snugly receive the described cross-bar terminal, thereby maintaining the plane of the respective bar webs 16A and 17A in substantial alignment with the plane of the panel 10 when the upstanding web flanges are all faced in one and the same direction.

A distinctive structural feature of my built-up framework resides in the novel formation given to the respective corners thereof; the rectilinear bar sections may each be perimetrical rounded to constitute an overlapping

corner region of sector shape such as is depicted in Fig. 4. These intersecting bars are interconnected by the tongue 19 along one radially disposed edge of said shape while the complementary tongue 18 clinches together the superimposed bars along the rounded perimetric edge thereof. The clinchable, panel retaining prongs 14 and 15 are shown spaced-ly associated with opposite end regions of the rounded contour of said sector shape to lie within the projected width confines of the respective sheet metal strips of which they form an integral part. In the Fig. 7 disclosure, the exposed exterior face of the socket 26 is kept raised outwardly beyond the offset 29 to provide for a corner trim that protrudes upwardly relative to the intermediate face portion of the frame-bar 16.

After these complementary bar ends are nested together, the entered side-tenon or tongue 19 is clinched into its contiguous aperture 23 and the depending end-tenon or tongue 18 is permanently crimped over the underlying edge of its mated bar in the fashion represented in Fig. 4. It will be observed that the root of the overhanging tenon 19 is sharply bent and the free end thereof brought into substantial alignment with the innermost rail flange 16B, to the end that said free end may be unrestrictedly entered into the aperture 23 without defacing the front face when the overlapping rail web apertures are superimposed as shown in Fig. 1. Each of the overlapping frame corner regions are similarly treated, which provides the perimeter of the interconnected framework with rearwardly upstanding prongs such as 14 and 15 adapted to receive and be inturned over the rear face of the license plate 10. (See Figs. 2 and 4).

It is preferred to have more than one prong embrace each of the marginal edges of the rectangular panel 10; when desired, these prongs can be repeatedly bent up to allow of panel replacement. The overall frame dimensions are preferably chosen to make the innermost perimeter of my interconnected bars center in the plate groove 12, the overhanging prongs being kept sufficiently long to reach inwardly over and press upon the rear of such groove-forming wall as shown in Fig. 3. In the present invention, the innermost web flanges are all brought down flush upon the front face of the license plate in an inwardly centered relation to the marginal bead thereof and the separate bar fastening means together with the associated depending prongs, are confined to and located within their respective intersecting bar regions.

Where the license plate affords no such groove, I provide for additional anti-shift measures by springing the panel 10 into its frame. As will be understood, such state license plates have become fairly well standardized as to size and disposition of

beads. These plates are usually provided with spaced bracket slots 25A and also with a pair of corner securing holes 25B thru which said plate may be bolted to a suitable holder bracket such for instance, as the drilled, relatively short flange 27 which is commonly suspended from the tail light of an automobile and may be interposed between the prong spacing given to my framework. Assuming that the bottommost prongs have not as yet been inturned, then by drawing up a pair of large-headed bracket bolts such as 28 respectively entered through the uppermost plate slots 25A and also the flange 27, the assembled trim frame may be made to tilt outwardly away from the front panel face in the fashion indicated in Fig. 9. The lowermost frame portion may now be manually sprung inwardly into place as shown in dotted outline, whereupon the adjacent upstanding prongs are inturned around the rear of the embraced plate to retain the frame thereon in the desired anti-rattle relationship.

A further important aspect of my frame structure lies in forming up segmental blanks from strip-stock that require no further shearing along the longitudinal edges thereof and in so shaping up the respective overlapping channel-like terminals, that no weld or separate keeper means will be required for corner securement purposes. It is not essential however that each segmental bar be equipped with duplicate prongs since certain of such prongs may readily be eliminated without loss of effective plate securement.

In some instances, it is found expedient to resort to bolts as a substitute for my prong means, and to this end there will now be described an alternative fastening means embodying substantially similar underlying features as far as bar structure is concerned. Referring to Figs. 10 and 11, each end of the side-bar 30 is again offset at 31 and socketed in a somewhat modified raised fashion having a squared hole stamped therethrough. Each cooperating male end of the cross-bar 32 is likewise provided with an aligning square hole and shaped to nest within the female or socketed side-bar end. For clamping purposes, a special flat-headed clamping screw 33 may be used having a square-shouldered shank portion 34 adapted to snugly fit into the complementary bar holes as represented in Figs. 10 and 12. There is further provided an apertured retaining or backing plate 35 that extends inwardly over the rear panel face and clamps upon the interposed marginal edge of the panel 10 when the rear nut 36 is applied to the threaded end of the entered clamping screw. Fig. 12 cross-sectionally indicates how the outermost shoulder edges of the shank 34 may by the use of a suitable riveting tool be burred over its contiguous bar aperture at 34A so as to fixedly interlock the assembled segmental frame-

bars while allowing the respective backing plates to be individually released therefrom.

The exposed head-face of these corner bolts may be jeweled or otherwise given a decorative design, the structural arrangement being such that said bolts interlock the bar segments and at the same time removably fasten the panel behind the framework without need of any prongs or special panel drilling. It will be observed that at each intersecting corner region of this rectangular frame, the web of one overlapping bar is suitably raised to pass its mate and again allow each medial bar portion to fall in a common plane.

Figs. 13 to 15 are illustrative of a reverse-ly mounted socket in which the abutting frame bars form a mitered joint. The dished bar 38 is here cut off along the beveled part-line 39 from which there extends a depending tenon 40. The complementary bar 41 has its overlapping end reversely offset at 42 to abut with said part-line. The web of the bar 41 may be extended outwardly and depressed into the tongue-like member 43 adapted to underlie the intersecting web portion of the bar 38. Adjacent to the offset 42 is located a tenon receiving aperture 44 and the extremity of the tongue 43 may be provided with an overhanging prong 45. In this instance, these cooperating bar terminals may be assembled in the manner shown by the interior corner view Fig. 15 where said prong 45 may be riveted to its contiguous bar flange as indicated at 46. In such alternative design, the front face of my segmental frame has been brought wholly into alignment with the abutting bar ends mounted in flush relation.

The shape given to my nested bar terminals preferably remains the same irrespective of the blank length and may readily be formed up by the use of extensible, sectional dies adapted to fit different bar lengths. My method produces a relatively rigid segmental frame structure and may be applied to uniting intersecting corner regions where the bars are to be obliquely disposed to form a rhomboidal or triangular contour. The defined novel mode of frame manufacture especially lends itself to rapid quantity fabrication at a sufficiently low production cost to enable this article to be profitably retailed through chain store agencies. In the present invention, the intersecting bar terminals are extended to overlie each other in either an external or internal relationship without requiring any separate keeper or interlocking elbow pieces for corner securement purposes. It will further be obvious all my bar blanks may be made alike by forming one end with tenons or tongues as in Fig. 5 while the opposite end thereof is provided with an aperture 28 as in Fig. 6. It may also be emphasized that in my frame corner structure, the tenons 18 and 19 are preferably associated

with different, spaced apart rail edges so as to afford a relatively non-yieldable joint between the intersecting rail regions should the frame be subjected to unsparing twist or the like weave.

Other advantages inherent in my frame devices are thought apparent to those skilled in this art, also that the corner structure thereof may be utilized in other associations and detail changes resorted to in likewise carrying out my various illustrative embodiments, all without departing from the spirit and scope of my invention heretofore described and more particularly pointed out in the appended claims.

I claim:

1. A segmental sheet-metal framework adapted to trim the perimeter of a panel, said frame comprising a pair of spaced rectilinear side-bars that are channel-like in cross-sectional profile and each including a web disposed to overlie one panel face and having a flange depending toward said face from the innermost edge of said web, and which frame further comprises a complementary pair of rectilinear cross-bars of like profile and web disposition having their respective ends extended in a bridging overlapping relation to said side-bars, each such intersecting bar region including a socket-like web offset for one of the overlapping bars and a male element integrally associated with the web of its other mated bar adapted to nest crosswise within the web offset of said one bar, and fastening means interconnecting the respective web offsets to their contiguous male elements to constitute an endless framework of which the component web flanges depend from the innermost frame contour and the respective free flange edges lie in a common plane.

2. In a segmental sheet-metal trim frame for mounting a license plate therebehind and which plate is provided with a marginal bead, the combination of a pair of spaced rectilinear side-bars of channel-like cross-sectional profile each provided with a web element having an outstanding flange that overlies the plate perimeter and extends inwardly of the marginal bead thereof, complementary cross-bars of like profile and size of which the web elements are respectively disposed in a bridging overlapping relation to those of the first named pair of bars with the respective web flanges of all such bars directed rearwardly toward said panel, each such intersecting web region including a notch indented in the outstanding flange of one bar thereof serving to transversely receive the contiguous web element of the other bar with their respective medial bar portions kept in substantial alignment, and fastening means for uniting each of the respective intersecting web regions.

3. A segmental trim frame adapted to mount a panel therein, said frame comprising

ing a pair of rectilinear strip metal side-bar sections of which one bar end region terminates in clinchable prong means which prior to clinching is confined within the strip width dimension and has flexible tongue means associated therewith and which frame further comprises a pair of cross-bar sections each having an aperture adjacent to an end region thereof and which cross-bar apertures are respectively disposed to cooperatively receive and interlock with a contiguous side-bar tongue for the purpose of uniting said sections into a framework provided with a plurality of perimetricaly depending prongs which upon being clinched inwardly serve to embrace the edge of the panel.

4. An endless sectional moulding adapted to circumscribe a panel, said moulding comprising a pair of strip metal, rectilinear bar-segments of which one is provided with a raised transverse offset located inwardly from a terminal region of said one bar to constitute an extension overhanging the bar offset, and the other of said bar-segments having a terminal region overlappingly superimposed upon and nested in said extension in abutment with said offset, one such segment being provided with a tongue receiving aperture and its mated segment having a cooperating tongue serving to unite the overlapping region of the bar-segments, and clinchable prong means integrally appended to one of the bar-segments in the overlapping region thereof, said means prior to being clinched lying within the strip width confines of said one segment and disposed to be clinched inwardly over a marginal edge of the panel.

5. The combination of a rectangular plate with front and rear faces having a slot adjacent to one plate edge, a support bracket adjoining the rear plate face and which bracket is provided with an aperture registering with said slot, an endless trim frame including a plurality of bars certain of which are each equipped with a prong and which frame is arranged to overlappingly circumscribe the marginal edge of the front plate face with one such prong initially crimped over the aforesaid one plate edge, and clamping means entered through the plate slot and the bracket aperture and including enlarged head means disposed to straddle the plate and the bar lying contiguous to said slot, said means when clamped toward the bracket tilting another pronged frame-bar outwardly away from the plate and the prong of the last named bar being sprung inwardly and inturned over the rear plate face to provide for an anti-rattle mounting of the plate within said frame.

6. An endless sectional framework adapted to be mounted upon a panel having front and rear faces, said framework being disposed ahead of the front panel face and comprising a pair of intersecting bar-segments, the overlapping terminal region of one such

- segment being provided with flexible tongue means and the adjoined terminal of the other segment underlying said one segment and having a registering aperture into which the 5 free end of said tongue is clinched in concealed relation between the framework and said panel, and longitudinally disposed prong means appended to the terminal region of one of the intersecting bar-segments, said 10 prong being inturned over the marginal edge of the rear panel face in a superimposed relation to its contiguous tongue.

7. A sectional moulding comprising a pair of adjoining, strip metal bar segments disposed to intersect in oblique relation of which one such segment is provided with an offset extension means and the other segment is overlappingly superimposed upon said extension in nested relation, fastening means 15 interconnecting said superimposed bar elements and which means constitutes the sole securement between said pair of adjoining bars, and prong means integrally carried by and extending outwardly beyond the intersecting region of one such bar and which 20 prong is initially disposed within the projected longitudinal edge confines of the bar strip of which it forms an integral part.

8. A segmental framework comprising a 30 pair of rectilinear, strip-stock bars superimposed to intersect in oblique relation to constitute an overlapping corner region of sector-like shape having a rounded perimeter for each such bar and which bars extend oppositely away from the respective radial marginal edges of said sector shape, integral tongue means carried by one of said bars medially of its rounded perimeter and which tongue is clinched over the rounded perimeter 35 of the other bar, and cooperating tongue means associated with one of the radial edges of said sector shape.

9. A segmental framework comprising a 45 pair of rectilinear, strip-stock bars superimposed to intersect in oblique relation to constitute an overlapping corner region of sector-like shape having a rounded perimetric frame edge and which bars extend oppositely away from the respective radial marginal 50 edges of said sector shape, prong means integrally associated with one such bar at the end region of the rounded perimetric edge thereof, and fastening means securing together the intersecting bars.

- 55 10. A segmental framework comprising a pair of rectilinear strip-stock bars superimposed to intersect in oblique relation to constitute an overlapping corner region of sector-like shape having a rounded perimetric 60 frame edge, a pair of tongues of which one is associated with said rounded perimetric edge and the other with a radial marginal edge of said sector shape, and prong means disposed intermediate said tongues.

- 65 11. An endless segmental moulding of par-

alleogram contour adapted to overlie and trim the marginal edge of an inserted panel, said moulding comprising a pair of intersecting bars that are each rectilinear throughout the respective lengths thereof and having 70 their intersecting regions shaped to form a rounded corner for said moulding, said bars each being given a cross-sectional channel shape including a flange component associated with the innermost edge of said endless 75 moulding, integral bar prong means extending from the outermost moulding perimeter, and fastening means interconnecting the aforesaid intersecting pair of adjoining bars.

In testimony whereof, I have herewith set 80 my hand this 7th day of January, 1932.

UDO K. JOHANNSEN.
